ELECTRIC FUEL PUMP

Carleton J. Lauer and Roy L. Bowers, Flint, Mich.,
assignors to General Motors Corporation,
Detroit, Mich., a corporation of Delaware

Application April 23, 1937, Serial No. 138,485

4 Claims. (Cl. 103—118)

This invention relates to the fuel supply system for engines such as are used on motor vehicles, on boats, aircraft, and in stationary power plants. It is more particularly concerned with the delivery of fuel from the reservoir or tank to the remotely located engine. It is intended to replace such older means of delivering fuel as the vacuum tank and the engine operated suction producing pump. In both these older well known forms, the fuel, flowing from the reservoir under the influence of reduced pressure, has had a tendency to vaporize under excessive heat conditions and it is one of the primary objects of the present invention to devise a fuel supply system which shall avoid the disadvantage of fuel vaporization and "vapor lock" which, in the case of an engine operated pump, has interfered with the delivery of liquid fuel to the float bowl of the carburetor.

Among other objects to be attained are substantially noiseless operation, high pumping capacity, promptness in delivering fuel, comparatively low pump speed, an arrangement whereby faulty engine operation is avoided when liquid fuel becomes vaporized in the pipe line, an improved arrangement for freeing the fuel from foreign matter, and an improved means to insure lubrication of the motor shaft bearings in the case of an empty fuel tank.

Other objects and advantages will be understood from the following description:

In the drawings showing an illustrative embodiment of the invention:

Figure 1 is a transverse section through a gasoline tank of a motor vehicle showing the novel pump mechanism therein.

Figure 2 is a vertical section through a part of the pump mechanism.

Figure 3 is a similar section through the motor and pump assembly.

Figure 4 is a section on line 4—4 of Figure 3.

Figure 5 is a section on line 5—5 of Figure 4.

Figure 6 is a section on line 6—6 of Figure 4.

Referring by reference characters to the drawings, numeral 11 represents a fuel tank such a tank as is carried by a motor vehicle. The tank may include an upper part marked 13. There is also shown in the drawings provision for draining the tank at 15.

The invention contemplates the support of a combined motor and pump assembly and spacer from the top of the tank, the whole assembly to be located within the tank. For supporting the motor, pump, and spacer, there is provided a ring of rubber or the like 17 peripherally overlying the marginal wall 19 of a tank opening 21. A metal-

lic ring 23 rests upon the rubber ring over the wall 19 and fastening means 25 clamp the parts in position as shown.

The pump mechanism includes a motor and pump assembly designated as a whole by numeral 27 and it also includes, in the case of a large tank, a spacer 29. The spacer is as shown, a cylindrical member secured above and to the motor and pump assembly 27 by fastening means 31. At the top of the spacer 29 is an annular 10 flange 33. A metallic ring 35 overlies the inner peripheral edge of the rubber ring 17 and fastening means 31 serve to clamp the ring 35 and the rubber ring to the flange 33. It will be seen from Figure 1 that the pumping mechanism as a whole, 15 does not rest on the bottom of the tank but that it is wholly supported by the rubber ring 17. One advantage arising from this type of support is the prevention of noise which would occur if the motor vibrations were transmitted to and amplified by the fuel carrying tank. The spacer 29 is formed internally with a vertical passage 39 extending to an opening 41 adapted to be connected in any convenient way with a conduit for supplying the engine. Openings 43 and 45 afford 25 communication between the passage 39 and the main chamber of the spacer. At the top of the spacer is an insulated post 40 for connection with a suitable wire not shown, for supplying electric energy. From this post a wire 47 extends through 30 the spacer 29 to a post 49 whereby the electric energy is communicated to the motor.

The motor and pump assembly comprises a tubular shell 51 with a top cover 53. The tubular shell is formed with a base 55. The rotor element 35 57 of the motor is carried by shaft 59. This shaft is mounted in spherical bearings 61. Preferably the bearings are of porous oil absorbing metal and are supplied with lubricant by saturated felt washers 63 located within recesses of the cover 40 53 and the base 55, the felt washers and bearings being secured by suitable retainers. The axial slot shown at the right of the felt washer of the upper bearing permits gasoline to saturate the washer. If, after standing for some time, the 45 gasoline level in the motor chamber falls below the level of the washer, the gasoline which is retained in the annular washer lubricates the upper bearing. The brush carrying plate 65 is spaced by a paper collar 67. Bolts 69 hold the cover 50 assembled with the base. A stand pipe 71 is press-fitted into an opening of the base. It extends through a somewhat enlarged opening 13 in the top cover 53 and into the lower end of passage 39. The base 55 is cast to form a recess constitut- 55

ing the housing for a gear pump. A bottom cover 75 forms a closure for the pump chamber. The motor shaft 59 beneath its lower bearing 81 is reduced in diameter as at 77, carries a gear 79 and its lower end rests on a ball 81 located in a recess of the cast cover 75. This ball provides an anti-friction support and thrust bearing for the rotor element of the motor. Cooperating with gear 79 is a gear 82 meshing therewith, the two gears constituting a gear pump having an inlet 83 and an outlet 85, the outlet leading to a space beneath the stand pipe 71. A bottom closure 87 is secured to cover 75 and base 55 by fastening means 89, there being a gasket 15 between parts 75 and 87 as shown at 91. A somewhat arcuate recess 93 is shown formed in the cap 87. By means of a suitable opening 95 in cover 75, this recess is in communication with the space 85 beneath the stand pipe. The recess 20 93 leads to an opening 97 formed in the cover plate 75 and through said opening to a chamber 99. This chamber, as shown in Figure 5, is located between walls 75 and 55 and is surrounded by a fire screen 101 whereby the chamber is separated from the larger region between parts 75 25 and 55. The flow of fuel to the chamber 99 is resisted by a valve disc 103 held against the seat 105 located within opening 97 by a spring 107, the latter being positioned by guides 108. Between the parts 87 and 55 is a vertical walled cylindrical filtering screen 109. A hollow inverted cup 111 is made fast to the side wall 51 and extends down outside the screen 109 but terminates above the bottom of the lower face 30 of the pump gears. A small opening 113 is provided near the top of the screen 109 within the cup 111.

In the operation of the device, the motor drives the gear pump which takes fuel from the tank 40 through the filtering screen 109 and the inlet 83. It delivers the fuel to the outlet 85 whence the fuel travels up through the stand pipe 71. Fuel overflows from the stand pipe at 73 and fills the motor chamber. It then fills the passage 45 39 and the larger chamber of the spacer. In so filling these chambers the air is forced through the outlet 41. This filling of the chamber requires but a few seconds. Thereafter the fuel is delivered through outlet 41 to the carburetor 50 of the engine. The use of a gear pump is of considerable importance in that it may be driven at comparatively low speeds. In this way much noise is avoided. This is very desirable because any noise, if transmitted to the tank is greatly 55 amplified. Moreover by the use of a noise absorbing support 17 substantially all transmitted noise is avoided. Also of importance is the fact that the efficiency of the pump is such as to overcome the pressure of any vapor developed in the system. When the car is stopped there is an ample supply of fuel in the stand pipe and within the overlying chambers to keep the pump chamber full of fuel. It is to be noted that the 60 bearings for shaft 59 are substantially fluid tight. This is of particular importance in connection with the lower bearing. Such a quantity of fuel is carried by the motor chamber that the bearings are supplied with lubricant for many hours after the tank is empty for the reason that the 65 lower bearing effectively resists the escape of fuel. Inasmuch as the pump must supply fuel for maximum demands, the excessive delivery of the pump under normal driving conditions results in a flow of fuel through the by-pass. In the event 70 that the car is stopped and the pump becomes 75

idle it is possible that vaporized fuel might force all the liquid fuel from the pump and also force it out through the valve 103 and the screen 101 into the space within the filter 109. This it would do rather than flood the carburetor.

Under some circumstances it might happen that the fuel vapor would remain within the filtering screen 109. Except for the provisions about to be described, this might force all the liquid fuel out from within the filter 109 and the pump might start with difficulty because its gears would be dry. To prevent any such occurrence there is provided the opening 113. The fuel vapors will find a ready escape through this opening and if sufficient in quantity they will escape from under the edge of the cup 111. It will be noted that the bottom edge of the cup is above the bottom of the pump gears so that the gears will be constantly wet with liquid fuel which will be sufficient to effectively start the pump.

It has been found that the cylindrical vertical wall screen 109 is kept clean by the fuel as it sloshes about in the tank. Another advantage resulting in the specific construction described is concerned with the thrust bearing for taking the whole load of the rotating parts. This is the ball bearing 81. Owing to the anti-friction contact between shaft 77 and the ball 81 starting of the pump mechanism is particularly easy. 30

Since the stand pipe 71 extends to a point above the motor the motor remains submerged in fuel even after the tank is drained. This is true because there is substantially no leakage about the lower bearing of shaft 59. The bearings for the rotor are thus always plentifully supplied with lubricant, sufficient for a long period of time after the fuel in the tank is exhausted. 35

The by-pass and its valve are located substantially at the bottom of the tank so that no turbulence or aeration can occur. If a car so equipped were left standing for months there might be an explosive mixture of gases which would be ignited by sparks at the brushes but the fire screen 101 would prevent any flame propagation to the fuel in the tank. 40

It should be added that in the case of a shallow tank the spacer may be omitted. When so omitted an outlet such as 41 in Figure 2 will be provided at the top of the motor unit and the stand pipe will be in open communication therewith as it is in open communication with the passage 39 in Figure 2. In other respects the arrangement for a small tank will be the same as 55 above described. 50

We claim:

1. In combination, a fuel tank, a combined motor and pump assembly, means to support said assembly from the top of said tank, said assembly including a pump and a superposed motor, said motor being located within a motor chamber, said motor chamber having upper and lower end walls, means to rotatably support the rotor of said motor in said end walls, the rotatable support in the lower end wall being constructed to minimize escape of liquid, a stand pipe forming the discharge passage of said pump, said stand pipe having its upper end open to the motor chamber means to admit fuel from the delivery end of the stand pipe into the top of the motor chamber whereby the latter may be supplied with fuel from the pump for lubrication and whereby the lubricating medium may be retained in said chamber when the pump is idle, 75

and other means whereby the fuel may be delivered externally from the stand pipe.

2. The invention defined by claim 1 together with a spacer above said motor and pump assembly and secured thereto, said spacer secured to the top of said tank and housing said other means.

3. The invention defined by claim 1, said pump comprising a first gear carried by an extension 10 of the lower end of the rotor shaft of said mo-

tor, said assembly including a cover rigid therewith and an anti-friction thrust bearing in said cover engaged by the end of said rotor shaft extension.

4. The invention defined by claim 1, said supporting means for said assembly including a resilient ring secured to said tank and to said assembly. 5
